UNITED STATES PATENT OFFICE.

ERNEST L. BURRELL, OF CHICAGO, ILLINOIS.

POWER-TRANSMISSION BELT.

1,396,925.

Specification of Letters Patent. Patented Nov. 15, 1921.

Application filed May 9, 1917. Serial No. 167,411.

To all whom it may concern:

Be it known that I, ERNEST L. BURRELL, a citizen of the United States of America, and a resident of Chicago, county of Cook, and 5 State of Illinois, have invented certain new and useful Improvements in Power-Transmission Belts, of which the following is a specification.

The main object of this invention is to provide an improved form of power transmission belt built up of superimposed layers of fabric, so as to be fully as durable as leather belting, and in all respects a practical substitute therefor, yet materially less expensive.

15 The several views shown in the accompanying drawings illustrate the manner in which the improved belt is manufactured and some of the conditions incident to its use.

Figure 1 is a perspective view of a section 20 of the thick cotton belting material which forms the body of the belt.

Fig. 2 is a section of the thin, closely woven sheet material out of which the remainder of the belt is built up.

25 Fig. 3 is a section of the completed belt.

Fig. 4 is a diagrammatic view illustrating the manner in which the belt wraps around a pulley.

Fig. 5 is a diagrammatic view illustrating 30 the relative stretching and compressing stresses within the belt as it passes over a pulley.

Fig. 6 is a perspective view of the belt as applied for use with tight and loose pulleys, 35 so as to be shifted from one to the other.

The materials which enter into the manufacture of this belting are two kinds of fabric and a glue composition. One fabric 7 is a thick, coarsely woven material commonly 40 known in the trade as "cotton-woven belting," such as is extensively used in the manufacture of various kinds of belting. The other fabric 8 is a comparatively thin and rather finely woven material, such as might 45 be designated a light-weight canvas. The kind preferably used is commonly known in the trade as "army duck."

Various kinds of cement can of course be used with perhaps varying results. That 50 which has been found most satisfactory is a composition of paper pulp and hide or bone glue, such as has been described in my Patent No. 1,116,237, granted November 3, 1914.

The improved belting is manufactured in 55 substantially the following manner:

First, a strip of the coarse fabric 7 is thor-

oughly coated on one face with a quantity of the composition glue, upon which is placed the first layer of thin fabric 8, which is also coated with the glue. These two layers are 60 then put under pressure and allowed to stand until thoroughly dry. Next, a second layer of thin fabric 8, thoroughly coated with the glue composition, is applied in a similar manner upon the first layer of fabric 8, and al- 65 lowed to dry under pressure. This is re-peated until the combined thickness of the layers of thin fabric 8 is substantially the same as the thickness of the coarse fabric 7.

This process of building up the belt and al- 70 lowing each layer of the fabric 8 to thor-oughly dry under pressure before another layer is applied, causes the layers of the fab-ric 8, on account of their comparative thin-ness, to become thoroughly saturated or im-75 pregnated with the glue composition, so that said thin layers are formed into practically a homogeneous mass. In a way, these thin layers of fabric might be said to comprise one ply, and the layer of coarse fabric 7 an-80 other ply of the belt. Although the glue composition does not impregnate the pores and meshes of the fabric 7 to the extent that it does the thin layers, yet said glue compo-sition is caused to penetrate considerably into 85 the pores and meshes of the adjacent face of the fabric 7, so that the two plies or sections of the belt are firmly united.

It is quite important that in building up 90 this belting, the combined thickness of the layers of fabric 8 be substantially equal to the thickness of the fabric 7, so that the juncture of the two plies or sections of the belt is substantially halfway between the outer sur-faces thereof. Thus, when the belt is trav-95 eling around a pulley, as shown in Fig. 4, the juncture is in a neutral position between the compressional stresses of the innermost sec-tion and the tensional stresses of the outer sec-tion. The relative extent of these stresses 100 is diagrammatically represented in Fig. 5, where the line 9 represents the length of the semi-circular line 9.1 of Fig. 4, and the lines 10 and 11 represent the lengths of the semi-circular lines 10.1 and 11.1 respectively, of 105 Fig. 4. It will be observed that the line 10 is as much shorter than the line 9, as the line 11 is longer, which indicates that the amount of compression of the inner section of the belt at any particular point is proportionally 110 the same as the stress of the outer section at any particular point. These stresses being

thus neutralized at the middle plane of the belt, there is no stretching and compressing of the belt along said line of juncture, and thus little, if any, tendency to separate the 5 plies.

The belting is usually used with the layer of fabric 7 facing inwardly, as it is the more susceptible to compression without materially affecting its texture, whereas the layers of fabric 8, being so thoroughly impregnated with the glue composition, are quite firmly secured together and are more susceptible to the tensional strains.

Another very practical and beneficial advantage which is a feature of this belting is that excessive wearing along the lateral edges thereof does not produce fraying, as is usually incident to other kinds of fabric belting. This is due to the fact that the 10 edges of layers of fabric 8 present a mass of thread ends embedded in the glue composition. It is therefore possible to make use of this belt in connection with power transmission, where it is necessary to use a belt shifter 15 for moving the belt from one pulley to another, as has been illustrated in Fig. 6.

Although but one method of preparing this belting has been shown and described, it will be understood that the character of 20 the material and method of building it up may be varied or modified without departing from the spirit of the invention as defined by the following claims.

I claim:

- 35 1. A power transmission belt, comprising two superimposed plies of fabric firmly secured together by cement, one ply consisting of coarse woven strands, and the other consisting of fine woven strands, said plies being of substantially equal thickness so as to locate the juncture between them in a neutral position between the compressional and tensional strains to which said belt is subjected when in use.
- 40 2. A power transmission belt, comprising two superimposed plies of fabric firmly secured together by cement, one ply consisting of a single thick sheet of coarse woven strands, and the other consisting of a multiplicity of thin sheets of fine woven strands, said plies being of substantially equal thickness so as to locate the juncture between them in a neutral position between the compressional and tensional strains to which 45 said belt is subjected when in use.

3. As an article of manufacture, a power transmission belt, comprising a comparatively thick layer of fabric, and a plurality of comparatively thin layers of fabric superimposed upon one face of said thick layer of 60 fabric, said thin layers of fabric being secured together and upon said thick layer by cement which has been caused to fill the pores and meshes of said thin fabric, so as to combine the strands of said fabric and the 65 cement to constitute substantially a homogeneous mass.

4. As an article of manufacture, a power transmission belt, comprising a comparatively thick layer of fabric, and a plurality of comparatively thin layers of fabric superimposed upon one face of said thick layer of fabric, said thin layers of fabric being secured together and upon said thick layer by cement which has been caused to 70 fill the pores and meshes of said thick fabric so as to combine the strands of said thin fabric and cement to constitute a substantially homogeneous mass, the combined thickness of said superimposed cement-im- 75 pregnated thin layers being substantially the same as the thickness of said one thick layer of fabric, so as to locate the juncture between said thick layer and said plurality of thin layers in a neutral position between the 80 compressional and tensional strains to which said belt is subjected when in use.

5. As an article of manufacture, a power transmission belt, comprising a layer of comparatively thick, coarse, woven cotton 90 belting material, and a plurality of layers of comparatively thin, fine woven material superimposed on one face of said thick layer, said thin layers of fabric being secured together and upon said thick layer by cement 95 which has been caused to fill the pores and meshes of said thin layers, so as to combine the strands of said thin fabric and cement to constitute substantially a homogeneous mass, said cement being also caused to penetrate into the pores and meshes of the adjacent face of said thick layer, the combined thickness of said superimposed cement-im- 100 pregnated thin layers being substantially the same as the thickness of said thick 105 layer.

Signed at Chicago this 7th day of May, 1917.

ERNEST L. BURRELL.
